Primary Examiner — Selina Sikder(74) *Attorney, Agent, or Firm* — Perkins Coie LLP(57) **CLAIM**

The ornamental design for a light emitting diode, as shown and described.

DESCRIPTION

FIG. 1 is a perspective view of a light emitting diode showing a new design;

FIG. 2 is a front view of the light emitting diode;

FIG. 3 is a rear view of the light emitting diode;

FIG. 4 is a left side view of the light emitting diode;

FIG. 5 is a right side view of the light emitting diode;

FIG. 6 is a top plan view of the light emitting diode; and,

FIG. 7 is a bottom view of the light emitting diode.
